A. E. HILTON.
CUTTING MECHANISM.
APPLICATION FILED NOV. 12, 1915.

1,273,368.

Patented July 23, 1918.

UNITED STATES PATENT OFFICE.

ARTHUR E. HILTON, OF NEW YORK, N. Y., ASSIGNOR TO R. HOE AND CO., OF NEW YORK,
N. Y., A CORPORATION OF NEW YORK.

CUTTING MECHANISM.

1,273,368.

Specification of Letters Patent. Patented July 23, 1918.

Application filed November 12, 1915. Serial No. 61,089.

To all whom it may concern:

Be it known that I, ARTHUR E. HILTON, a citizen of the United States, residing at New York city, county of New York, and 5 State of New York, have invented certain new and useful Improvements in Cutting Mechanism, fully described and represented in the following specification and the accompanying drawings, forming a part of the 10 same.

This invention relates to certain improvements in cutting mechanism, and has been designed particularly for use with the rotary cutters employed for cutting sheets with a 15 shear cut, so that they will have clean-cut edges, although the invention may, if desired, be used with other cutting mechanism.

It is the special object of the invention 20 to provide an improved construction for insuring the freeing of the severed leading-in edge of the material from the cutters and for directing such severed leading-in edge into the path provided for it after passing 25 the cutters, so that there will be no catching of such leading-in edge against the cutters or deflection of such edge out of its proper path after the cut.

For a full understanding of the invention, 30 reference may be had to the accompanying drawings, in which—

Figure 1 is a side view, partly broken away, showing the improved sheet-freeing devices as employed with rotary shear cutters;

Fig. 2 is a cross sectional view taken on the line 2—2 of Fig. 1;

Fig. 3 is a horizontal sectional view taken on the line 3—3 of Fig. 2.

Referring now to the drawings, the invention has been illustrated in connection with a cutting mechanism in which there are employed rotary cutting elements coöperating to produce a shear cut. As illustrated, these 45 cutting devices are in the form of bars 1, 2 suitably secured in rotary cutter carriers, as cylinders 3, 4. As is usual, provision is made for adjusting one of the bars relatively to the other, the cutter bar 2, in the particular construction illustrated, being so mounted and being so adjusted by the usual wedge construction 5.

In the construction illustrated, where rotary cutting devices are employed for pro-

ducing the shear cut, the cutting faces of 55 these bars are arranged angularly to each other, one of the bars cutting against the face of the other. In such constructions, the severed leading-in edge of the web is apt to be caught by the angular face of the cutter 60 bar and thus be deflected out of the path provided for it beyond the cutters. In accordance with the invention there are provided means for preventing this, by the use of which the sheet is positively freed from 65 the cutter bar, these means furthermore acting to contact with the sheet and to assist in forwarding the severed leading-in edge of the material into the path it is intended to take beyond the cutters. These means 70 will be of a flexible character, so that during the cutting operation they will be compressed against the sheet and put under tension, and after the severed leading-in edge of the material has passed the cutters they 75 will be released and free the sheet therefrom. While these means may be of various characters, in the preferred construction there will be provided a brush having bristles of suitable length to be compressed to the extent sufficient to provide the necessary sheet-freeing movement when they are released. In the particular construction illustrated, there is provided such a brush having three 80 rows of bristles 6, these bristles being carried in a block or bar 7, located in the cylinder 4 closely adjacent and in the rear of the angular cutter 2, which in this particular instance is a cutter having its cutting face extending angularly in a rearward direction. In the best constructions, this brush block 7 will be mounted in the cylinder so 85 that it can be readily detached therefrom. In the particular construction illustrated the brush block is supported on a transverse ledge 8 formed by grooving the cylinder, and is prevented from sidewise displacement by taking against the wall 9 of the groove and against a head 10 carried on a bolt 11, which also secures the cutter bar 2 in the 90 groove of the cylinder. The brush block 7 is held from upward displacement by a retaining device. While this device may have various configurations, as shown there are provided a suitable number of block-holding 95 arms 12 (one of which is shown) extending from a bracket 13 suitably bolted to the cylinder in a clearance formed therein, the

100 105

arm 12 bearing on the block between the bristles. By the removal of this arm or arms the brush block may be removed from the machine and another substituted. The 5 parts of the brush are compressed or put under tension, and are, as illustrated, bent backward by the action of the cutter carriers, and the brush, when it has passed the contact point of the carriers and is released, acts to instantly free the leading 10 end of the oncoming web from the cutter knives. By reason of the bending backward of the brush members during the contacting of the cutter carriers, these members 15 also have a springing forward movement which assists very materially in forwarding the leading end of the web.

In machines embodying the invention in its best form, means will be provided, 20 operating with the other cutter bar and bearing on the surface of the material opposite that on which the brush bears, for directing the severed leading-in edge of the material into the path it is to follow beyond 25 the cutters. In the particular construction illustrated, this is effected by providing a stripper bar 14 suitably secured to the cylinder 3, and located just behind the cutter 1.

With the construction illustrated and described the severed leading-in edge of the sheet is kept free of the cutters and is directed in the path provided for it to pass the cutters. While the construction shown and described for effecting this result is preferred, it will be understood that the details 35 of the construction may be varied without departing from the invention, and that the invention may be used with cutter mechanism other than rotary shear cutters.

40 What is claimed is:

1. In a cutting mechanism for severing material into lengths, the combination with the coöperating cutting elements, of a brush contacting with the material, the bristles of 45 the brush being compressed during each cutting operation and released after each cutting operation and acting to free the severed leading-in end of the material from the cut-

ting elements and to direct such end beyond the cutting elements. 50

2. In a cutting mechanism for severing material into lengths, the combination with a pair of rotating cutters, of a brush mounted behind and closely adjacent to one of the cutters and in contact with the material during and after the cutting operation and acting to free the severed leading-in edge of the material from the cutter, and a stripper 55 contacting with the side of the material opposite the brush. 60

3. In a cutting mechanism for severing material into lengths, the combination with the coöperating cutting elements, of a removable brush carrier and a brush mounted in the carrier, the bristles of the brush being 65 compressed during each cutting operation and released after each cutting operation and acting to free the severed leading-in end of the material from the cutters and direct such end beyond the cutters. 70

4. In a cutting mechanism for severing material into lengths, the combination with a pair of rotary cutter knives coöperating to produce a shear cut, of a brush removably mounted behind and closely adjacent to 75 one of the cutters and in contact with the material during and after the cutting operation and acting to free the severed leading-in edge of the material from the cutter. 80

5. In a cutting mechanism for severing web material into sheets, the combination with a pair of rotary carriers, of cutter elements carried thereby coöperating to produce a shear cut, a brush carrier removably mounted behind and closely adjacent to one 85 of the cutters and extending across the path of the web parallel with the line of cut, and brushes mounted in the carrier and in contact with the material during and after the cutting operation and acting to free the severed leading edge of the web from the cutter. 90

In testimony whereof, I have hereunto set my hand.

ARTHUR E. HILTON.
